UNITED STATES PATENT OFFICE.

JOHN A. HAGERSTROM, OF SCRANTON, PENNSYLVANIA, ASSIGNOR TO TECHNICAL SUPPLY COMPANY, OF SCRANTON, PENNSYLVANIA, A CORPORATION OF NEW JERSEY.

RULING-PEN.

1,305,538.

Specification of Letters Patent. Patented June 3, 1919.

Application filed May 1, 1918. Serial No. 231,835.

To all whom it may concern:

Be it known that I, JOHN A. HAGERSTROM, a citizen of the United States, and a resident of the city of Scranton, in the county of 5 Lackawanna and State of Pennsylvania, have invented certain new and useful Improvements in Ruling-Pens, of which the following is a specification.

This invention relates to the manufacture 10 of pens, and more particularly to ways and means of producing drafting instruments, such as pens for compasses, ruling-pens, straight-line pens, bow-pens, and the like.

It has been the common practice hitherto, 15 when manufacturing pens for compasses and similar instruments, to make the blades or legs thereof from a solid piece of metal, which was split by milling, in order to produce the opposed members that are designed 20 to hold the ink in drafting. The splitting naturally left a rough surface on each leg or blade, which had to be smoothed down and polished, that the flow of ink might not be interfered with or interrupted. This, however, 25 was difficult to accomplish, due to the very narrow slit produced by the splitting, which necessitated the employment of exceedingly thin grinding wheels, that is, the only kind that could be introduced between 30 the parted sections of metal that were to become the blades or legs of the instruments. The process of thus grinding and polishing the blades or legs was slow and tedious at best, and therefore uneconomical and unsatisfactory.

Primarily, the invention has for its object 35 to provide an improved mode of construction for drawing-pens, permitting the same to be made from a blank of sheet-metal, 40 which admits of being operated upon externally at first on either side, and subsequently can be bent upon itself to evolve the required shape, thereby enabling the manufacturer to polish in advance that face of the 45 blank which eventually will form the inside of the pen, by means of ordinary grinding-wheels.

A secondary object is to produce a blank 50 of the nature set forth that has within itself all the necessary elements to make up a complete pen, including a pair of narrow members wherewith to form the usual pen-points or ink-container and blades or legs, as well as a broad portion to fashion a socket for a 55 holder, and yet is capable of being folded

centrally without lateral projections, so as to assume at once the general contour of an ordinary pen such as draftsmen are accustomed to use.

An additional object is the provision of an 60 improved type of pen-holder that will immediately conform to the shape of the socket produced in folding the blank above mentioned, and thus truly coact therewith in supplying an instrument of approved outline, while obviating much grinding or laborious interfitting of parts, and simplifying the attachment of the pen proper to its holder.

Other objects and advantages of the invention will become apparent as the specification proceeds.

Succinctly described, the invention consists, first, in forming a blank of a single piece of sheet-metal composed of three integral sections, to wit, a pair of tapered members separated by a median slot extending longitudinally of the blank, and a substantially rectangular portion that constitutes a common base for the said members. An aperture of larger diameter than the width of the said slot is provided at the inner end of the latter, the same enabling the metal in the blank to contract inwardly at the bend thereof when folded axially along its longitudinal center, so that the doubling of the metal upon itself simply superposes the tapered members relatively one to the other and produces a laterally open socket at their said base, the opposite sides of which extend 80 equidistantly from the central line of fold. The blank is appropriately ground or polished before folding, and otherwise manipulated to adapt its several parts to the discharge of their respective functions when 85 transformed into a drawing-pen. Further, the invention consists in providing a holder with an eccentrically located element adapted for insertion between the opposite walls of the folded base portion of the blank, in 90 such a manner that the combined width of the said element and of the said socket will be commensurate to the transverse dimensions of the correlated parts of the drawing-pen and its holder near the points of junction.

The drawing hereto annexed illustrates a convenient embodiment of the invention, and the application thereof to various drafting instruments hereinafter specified.

In the said drawing:—

Figure I is a top plan view of a drawing-pen made in accordance with the invention, minus the holder;

5 Fig. II is a side view of the same;

Fig. III is a development of the blank for the pen proper;

Fig. IV is a transverse section on the line IV—IV of Fig. I, looking toward the point 10 of the pen, in the direction indicated by the arrows;

Fig. V is a similar section on the line V—V of Fig. II, looking toward the left;

Fig. VI is a top plan view, showing a 15 novel form of shank pertaining to a holder provided for one leg of a pair of compasses or dividers, the position of the pen relatively to the shank being indicated by dotted lines;

Fig. VII is a like view of a similar shank 20 adapted to a holder for a ruling-pen;

Fig. VIII is a partial side view of a bow-pen, also embodying the invention; and

Fig. IX is an end view of the shank shown 25 in connection with the pens represented in Figs. VI and VII.

The first step in carrying out the invention is to prepare the blank, which may be easily obtained by striking or cutting from sheet-metal, and preferably consists of a 30 single piece, as indicated by the numeral 1 in Fig. III. The metal, it is understood, may vary in thickness according to any particular description of drafting instrument to be produced.

35 As shown in its development, Fig. III, the blank 1 is slotted centrally lengthwise to provide therein a slot 2, by means of which it becomes bifurcated and divided into two equal parts, respectively designated by the 40 numerals 3 and 4, at one end. These parts are to constitute the blades or legs of the drawing-pen and may take up approximately three-fourths of the blank, the slot whereof is extended inwardly more or less 45 according to the purpose in view. The other end of the blank, which forms a base 5, common to the two said parts 3 and 4, affords the requisite material for a socket-piece, hereinafter described. At the inner extrem- 50 ity of the said slot 2, is also provided an aperture 6, of considerably larger diameter than the width of the slot at that point, and designed to effect the folding of the blank, the folding taking place on lines coinciding 55 with the opposite sides of the said aperture or enlargement 6 at the inner end of the slot 2, and being parallel to the opposed edges of the latter.

Taking the blank in its flat shape, as represented in the said Fig. III, it will be observed that no difficulty whatsoever is experienced in grinding and polishing the same preparatorily to forming the blades or legs of the drawing-pen, as compared with 60 the method formerly followed in fashioning

a similar instrument. Ordinary grinding wheels and polishing tools can be employed, for it is no longer necessary to have recourse to narrow grinders and polishers such as one was compelled to use when forming the 70 blades or legs of the pen by slitting a solid piece of metal, in accordance with the old practice. The inner faces of the pen's blades or legs can therefore be rendered as smooth as desired before superposition of one over the other, so that there will be no impediment to the flow of ink between the pen-points.

Besides affording ease and convenience in producing smooth surfaces on the members of the pen, it will be noted that the blank further admits of their being properly curved or rounded, both longitudinally and transversely, as well as tapered and pointed, previously to folding, all as indicated in the 80 drawing. Thus, for instance, the longitudinal curves shown in Figs. II and VIII, the oppositely-directed transverse curves appearing in Fig. IV, and the tapers and points exhibited in several other views can 85 all be produced while the blank still remains unfolded. The same is true of the holes usually provided for retaining and adjusting screws, as at 7, 8, 9 and 10. A material saving of labor and time is thereby effected 90 in the manufacture of the pen.

When all the work that can be done on the blank has been finished, the latter is folded centrally in the direction of its length 100 so as to bring the parts 3 and 4 thereof one above the other, as shown in Figs. I, II and VIII, which parts then constitute the paired members forming the blades or legs of the drawing-pen. The blades or legs are provided, as usual, with a retaining or adjusting screw to engage the holes 9 and 10, or with a set-screw 14, as indicated in dotted lines, Fig. VIII. The metal of the blank, it is understood, has sufficient elasticity to cause the blades or legs to spring apart as 105 either of the adjusting screws is being retracted. Besides, the blades or legs in each pair are held together at the end thereof remote from the pen-points, by the folded base portion 5 of the blank, previously referred to, which base upon being bent centrally upon itself becomes U-shaped in cross-section, as detailed in Fig. V. From this U-shaped portion out, the blades or legs gradually increase in elasticity, so that the instrument possessing the same has a great 115 range of adjustability and quickly responds to the touch of the draftsman using it.

The enlargement or aperture 6 at the inner end of the slot 2, hereinabove described, 120 causes the width of the sheet-metal of which the blank is composed to become contracted when forcibly bent axially on its longitudinal center in the operation of folding, to the extent that the middle section of the afore- 125

said base 5, constituting the closed part of the U-shaped end of the folded blank, does not project outwardly as it would if the blank merely had the central slot 2, without 5 the said aperture or enlargement. Or in other words the enlarged aperture permits the metal constituting the connecting portion between the opposite sides or faces of the base 5 to produce a fold which will lie 10 farther inward than it would if the said aperture was not provided. As shown by the dotted line in Fig. I, indicating the thickness of the closed side of the part 5, this closed side is well within the customary 15 width of a drawing-pen and the outer edge thereof practically coincides with the external edge of either one of the blades or legs forwardly of the aperture 6, thereby producing a pen corresponding in general 20 outline to that which draftsmen are wont to use.

As before alluded to, the said base portion 5 of the blank is utilized to form a socket, and thereby provide a ready means for attaching the drawing-pen to any suitable 25 form of holder. The socket-piece, it will be seen, consists of the U-shaped end of the folded blank, which being open at one side, as well as at the opposite extremities, is 30 well adapted to receive an interconnecting shank or stem, as 17, from some holder intended to carry the pen. But, it will be noted that the thickness of the closed part of the said U-shaped base would tend to push 35 the shank out through the open side, if the said shank were centrally positioned in the usual manner. This is avoided, in the present invention, by locating the shank 17 eccentrically, with relation to the holder to 40 which it appertains, as exemplified in Figs. VI, VII and IX. This improved form of shank is capable of use with a holder of any preferred make or construction. For example, as indicated in Fig. VI, the eccentrically positioned shank may be connected 45 to an ordinary holder for a pair of compasses; or as represented in Fig. VII, it may be joined to the handle of a ruling-pen; or as illustrated in Fig. VIII, it may form the 50 support of a pen for a bow-compass; and so on with holders for other drafting instruments.

Having described my invention, what I desire to secure by Letters Patent and 55 claim is:—

1. A blank for an instrument of the character described, including parallel members of approximately equal magnitude adapted

for superposition one above the other, a slot with an enlarged aperture at its inner end 60 separating said members, and said slot having substantially parallel edges for the major part of its length and diverging outer ends, a base portion common to both of the members beyond said aperture. 65

2. A blank for an instrument of the character described, consisting of a pair of relatively narrow members with an intermediate slot between the same terminating in an enlarged aperture, and said members having 70 substantially parallel inner portions with oppositely tapering extremities, a base section broader than the combined width of said members joining the latter beyond the enlarged terminal of said slot. 75

3. A blank for an instrument of the character described, including a pair of members adapted to be superposed one above the other, said members having inner portions substantially parallel at opposite edges and 80 outer portions tapering therefrom, and a base portion capable of folding to form a socket for said members open at one side and closed on the opposite side. 85

4. A blank for an instrument of the character described, composed of contractible sheet-metal divided centrally for the greater part of its length by a slot with an enlargement at the inner end thereof, and a base portion foldable on lines coinciding with the 90 opposite sides of said enlargement and parallel with the edges of said slot. 95

5. A blank for an instrument of the character described, including a pair of parallel members divided by an intermediate slot 95 having an enlargement at the inner end thereof, and a base portion foldable flatwise on opposite sides of said enlargement whereby an open-sided flat socket is produced. 100

6. An instrument of the character described, including a pair of members superposed one above the other in substantial parallelism, and a U-shaped socket integrally formed with said members, combined with a holder having an eccentrically positioned 105 shank arranged to enter said socket. 110

7. An instrument of the character described, including a pair of superposed members, and a base common to said members affording a socket therefor open at one side and closed at the other, combined with a holder provided with an eccentrically located shank adapted for insertion in said socket through lateral engagement. 115
